UNITED STATES PATENT OFFICE.

JOHN J. HEYS, OF LYNN, AND ALBERT R. BRADEN, OF BEVERLY, MASSACHUSETTS,
ASSIGNORS TO UNITED SHOE MACHINERY CORPORATION, OF PATERSON, NEW
JERSEY, A CORPORATION OF NEW JERSEY.

KNIFE FOR SPLITTING MACHINES.

Application filed January 30, 1924. Serial No. 689,471.

This invention relates to cutting tools and is herein illustrated as embodied in a knife for a leather splitting or skiving machine.

Such machines commonly comprise a pair of rolls for advancing the leather to a knife which is adjustably clamped to a flat support with its edge close to the bite of the rolls. These knives are sometimes made of a single piece of tool steel and sometimes 10 of a blade of tool steel welded to a body portion of low-grade steel. In either case the finished knife is rigid throughout and is really a one-piece construction. After knives of this kind have become sufficiently worn 15 away by successive sharpenings, they are discarded and replaced by new ones. Moreover, such knives, particularly when made entirely of tool steel, tend to become slightly distorted if allowed to stand in the stock room 20 for a few weeks, this distortion being probably due to the slots formed in them for the passage of the bolts by which they are adjustably clamped to the knife support.

With a view to overcoming these disadvantages, the present invention provides a novel two-part knife comprising a body portion and a replaceable blade. In the illustrative construction the body portion and blade are held together by a snap fastener so that the 25 two-part knife can be handled just as in the old form; and, in order to clamp the two parts firmly in place upon the knife support, a clamping member of particular form is provided. With such a construction the 30 blade can be removed and replaced when worn out, the body portion remaining intact; and the blades being of small extent and unslotted do not cause trouble by 35 warping.

This and other features of the invention, including certain details of construction and combinations of parts, will be described as embodied in an illustrative machine and pointed out in the appended claims.

Referring now to the accompanying drawings,

Figure 1 is a vertical longitudinal, sectional view of a portion of a leather skiving machine in which the present invention is 45 embodied;

Figure 2 is a plan of the two-part knife, and

Figure 3 is a detail in perspective show-

ing more particularly the means for holding the two parts of the knife together.

55

The machine chosen for illustration is a counter skiving machine of the general type of that shown in Patent No. 1,173,359, granted Feb. 29, 1916, upon an application filed in the name of Lane. It comprises a feed roll 1, a matrix roll 3, a series of presser-fingers 5 and a knife support 7 which is part of the frame of the machine and has a flat upper surface upon which the knife rests and over which the knife is adjustable. It 60 will be understood that the rolls are rotated in a direction to cause the leather blank to be fed to the knife which skives off that portion of the blank which projects above the matrix 9 of the roll 3. No further description of the construction and mode of 65 operation of the machine will be given, reference being made to the patent. Moreover, it should be understood that the particular type of machine which has been shown has 70 been chosen merely for illustrative purposes and that another type of machine such, for example, as a leather splitting machine 75 would have served as well.

The knife comprises a narrow blade 13 of 80 tool steel having a beveled cutting edge, and a body portion 15 of low-grade steel having a straight forward end 17 against which the straight rear edge of the blade 13 abuts. The two parts are detachably fastened together by a resilient snap fastener in the form of an open ring 21 of spring steel which is inserted in a circular groove 23, said 85 groove being formed partly in the blade 13 and partly in the body portion 15. The 90 spring ring holds the two parts of the knife together quite firmly so that the knife can be adjusted toward and from the rolls as may be required.

The knife rests, as shown in Fig. 1, upon the flat upper surface of the support 7. It is necessary to clamp the knife firmly in place, and it is especially desirable that the blade be clamped to the support as near the cutting edge of the blade as possible so that the edge shall not give or spring during the cutting operation. To this end as well as to ensure that the body portion 15 shall also be firmly clamped to the support 7 irrespective of any slight variation in thickness of the 100 105 blade and body portion, there is provided a

clamping member 25 in the form of a plate which is slightly hollowed out on its underside, as shown in Fig. 1. The rear portion of this plate engages the body portion of the 5 knife somewhat to the rear of its middle, while the forward portion of the plate engages the blade along a locality adjacent to its cutting edge. Cap screws 27 pass through suitable holes in the clamping plate and are 10 threaded into the knife support. The clamping plate thus holds the knife in adjusted position on the knife support in such manner that the tendency of the knife edge to spring during the cutting operation is 15 counteracted. In order to provide for accurate adjustment of the knife toward the rolls, two adjusting screws 29 are threaded into the knife support and engage suitable shoulders on the body portion 15 as shown. 20 Although the invention has been set forth as embodied in a particular construction, it should be understood that the invention is not limited in the scope of its application to the particular construction which has been 25 shown and described.

Having thus described our invention, what we claim as new and desire to secure by Letters Patent of the United States is:—

1. A two-part knife comprising a body 30 portion having a flat under surface, a blade of substantially the same thickness as that of the knife and also having a flat under surface, said blade being located in front of the body portion with the rear edge of the 35 blade abutting the front edge of the body portion, and a member for holding the parts together, said member being capable of manual manipulation from operative to inoperative position whereby the blade and 40 body portion may be readily detached from each other at any time.

2. A two-part knife for a splitting machine, said knife comprising a body portion, a blade and a resilient member for holding 45 the two parts detachably together, said body portion and blade having surfaces located in the same plane and adapted to rest upon a flat supporting surface of the machine.

3. A two-part knife adapted to rest upon 50 a support, said knife comprising a body portion and a blade, means detachable from the blade and body portion for holding the two parts detachably together, and means for engaging the two parts and clamping them 55 to the support.

4. A two-part knife adapted to rest upon 60 a support, said knife comprising a body portion and a detachable blade, means for holding the two parts detachably together, and means for clamping the two parts directly to the support, said clamping means 65 including a plate hollowed out on its knife-contacting face and contacting at its ends respectively with the body portion and with the blade.

5. A two-part knife for leather splitting machines comprising a body portion, and a replaceable blade, a resilient member adapted to hold them together, and means for clamping the parts to the support. 70

6. A two-part knife for leather splitting machines adapted to rest with both parts upon a support comprising a body portion, and a replaceable blade, a resilient member adapted to hold them together, and means 75 for clamping the parts to the support, said means comprising a plate hollowed out on its knife-contacting face and adapted to engage the blade along a locality near the cutting edge thereof. 80

7. A two-part knife for leather cutting machines comprising a body portion and a replaceable blade adapted to rest upon a support and means for clamping the parts directly to the support, said clamping means 85 comprising a plate hollowed out on that face which contacts with the parts of the knife.

8. A two-part knife for leather cutting machines comprising a body portion and a replaceable blade adapted to rest upon a support, the contacting edges of the two parts being straight, and means for clamping the parts directly to the support, said clamping means comprising a plate hollowed out on that face which contacts with the parts of 95 the knife. 90

9. A two-part knife for splitting machines comprising a body portion and a detachable blade adapted to rest upon a support with the rear edge of the blade abutting the front edge of the body portion, means whereby the two parts may be adjusted in unison over the support, and means for clamping them both directly to the support. 100

10. A two-part knife comprising a body portion and a detachable blade adapted to rest upon a support with two of their edges in contact, means whereby the two parts may be adjusted in unison over the support 110 and means adapted to engage the parts in two separated localities but not between said localities to clamp them directly to the support. 105

11. A two-part knife comprising a body portion and a replaceable blade adapted to rest in abutting relation upon a support, interengaging means for holding the two parts detachably together, a clamping member adapted to engage the blade along a locality adjacent to the edge thereof, and means for drawing the clamping member toward the support to clamp the two parts of the knife directly to the support. 115

12. A two-part knife comprising a body portion and a replaceable blade adapted to rest in abutting relation upon a support, interengaging means for holding the two parts detachably together, a clamping member adapted to engage the blade along a locality adjacent to the edge thereof, means for 125 130

drawing the clamping member toward the support to clamp the two parts of the knife to the support, and means whereby the parts may be adjusted in unison along the support.

13. A two-part knife adapter to rest upon a support, said knife comprising a body portion, an imperforate blade, means detach-

able from the body portion and the blade for holding the two parts detachably together, and means for engaging the two parts and clamping them to the support. 10

In testimony whereof we have signed our names to this specification.

JOHN J. HEYS.

ALBERT R. BRADEN.

CERTIFICATE OF CORRECTION.

Patent No. 1,628,840.

Granted May 17, 1927, to

JOHN J. HEYS ET AL.

It is hereby certified that error appears in the printed specification of the above numbered patent requiring correction as follows: Page 3, line 6, claim 13, for the word "adapter" read "adapted"; and that the said Letters Patent should be read with this correction therein that the same may conform to the record of the case in the Patent Office.

Signed and sealed this 11th day of October, A. D. 1927.

Seal.

M. J. Moore,
Acting Commissioner of Patents.
